UNITED STATES PATENT OFFICE.

RICHARD WILTSE, OF GRAND JUNCTION, IOWA.

ANCHOR-POST.

No. 809,879.

Specification of Letters Patent.

Patented Jan. 9, 1906.

Application filed January 28, 1905. Serial No. 243,590.

To all whom it may concern:

Be it known that I, RICHARD WILTSE, a citizen of the United States, residing at Grand Junction, in the county of Greene and State 5 of Iowa, have invented a certain new and useful Anchor-Post, of which the following is a specification.

The objects of my invention are to provide an anchor-post of simple, durable, and inexpensive construction which can be easily driven into the ground-surface at any desired angle relative thereto and in which post there is an anchor having two arms which can be adjusted vertically of the post 15 by means of a crank, so that the anchor can be firmly fixed in the ground after the post has been driven, and, further, to provide a device of this class in which the anchor can be withdrawn to a position inside of the post, 20 making it more easy to remove the post.

A further object is to provide a device of this class to which a cable or wire may be easily attached which is designed to be attached at its other end to a telephone, telegraph, or other post.

My invention consists in certain details in the construction, arrangement, and combination of the various parts of the device whereby the objects contemplated are attained, as hereinafter more fully set forth, 30 pointed out in my claims, and illustrated in the accompanying drawings, in which—

Figure 1 is a vertical sectional view of the post, showing the anchor-arms in their extended position. Fig. 2 is a vertical sectional view of the post, showing the arms in position at their inner limit of movement; and Fig. 3 is a side elevation showing the post in position in the ground and the crank 40 in position for moving the anchor so that the arms will be in their extended position. This view also shows the anchor-post connected with a telephone or telegraph post.

Referring to the accompanying drawings, 45 I have used the reference-numerals 10 and 11 to indicate the front and back portion of the post, which parts are connected at their upper ends by the top portion 12, having the openings 13 extending through it. The 50 lower portion of the parts 10 and 11 are connected with each other by means of the sides 14 and 15. Connecting these sides is the V-shaped lower end having the parts 16 and 17 therein. Between the parts 14 and 16 55 there is an opening 18, and between the parts 15 and 17 there is an opening 19, in

which the anchor-arms, hereinafter described, are designed to move. The above I have termed the "body portion" of the post for the sake of convenience. Connecting the 60 parts 10 and 11 and slightly below the central portion thereof is an anchor-post 20, having a screw-threaded opening in its central portion. Mounted in this support is a screw-threaded shaft 21, having a squared 65 upper end 22 and having the screw-threaded portion 23 thereon. The screw-threaded portion 23 is designed to coact with the screw-threaded portion of the anchor-support 20 to maintain the shaft in any position 70 of its vertical movement.

Rotatably mounted at the lower end of the shaft 21 is an arm-supporting lug 24, which lug 24 is held against vertical movement relative to the shaft 21 by means of 75 the keys 25 and 26. Pivots attached to the lug 24 by means of the pivot 27 are the anchor-arms 28 and 29, which are designed 80 when in their extended position to hold the post in position in the ground. These anchor-arms when at their inner limit of movement, have their lower ends extending partially through the openings 18 and 19, and as the shaft 21 is rotated in one direction the arms will be forced downwardly and out through 85 the openings 18 and 19 and into the position shown in Fig. 1. By rotating the shaft 21 in the opposite direction the arms are withdrawn from their extended position to the position shown in Fig. 2. I have provided 90 a crank-shaft 30, having a squared head 31 therein which is designed to fit over the squared upper end 22 of the shaft 21. This crank-shaft 30 is so constructed that its lower end can be inserted through the opening 13 and the head 31 can be placed on the head 22 of the shaft 21, which may be operated easily by the crank-shaft 30.

In practical operation the anchor-post is driven into the ground-surface at the desired 100 angle, with the anchor-arms at their inner limit of movement. When the post has been driven, the crank-shaft 30 is placed in the position shown in Fig. 3 and the shaft 21 is rotated by means of this crank-shaft 30 and 105 the arms 28 and 29 are forced into the position shown in Fig. 1, so that the anchor-post will be prevented from drawing out of the ground. The crank-shaft 31 is then removed. A wire or cable is attached to the 110 anchor-post and to the post which the anchor-post and the wire cable are designed to

support. Whenever it is designed to remove the anchor-post, the crank-shaft is again brought into use and the arms are withdrawn from their extended position, thus making it 5 comparatively easy to remove the post from the ground.

Having thus described my invention, what I claim, and desire to secure by Letters Patent of the United States therefor, is—

10 1. In an anchor-post, a body portion, a shaft rotatably mounted in the body portion, arms pivotally mounted near the lower end of said shaft and capable of being moved from a position inside of the post to a position 15 partially outside of the post as the shaft is rotated.

20 2. In a device of the class described, the combination of a body portion, a shaft mounted in the body portion and capable of vertical movement therein, arms pivotally mounted near the lower end of said shaft and connected therewith so arranged that as the shaft is moved in one direction the arms may be forced from a position inside of the post to 25 a position partially outside of the post, and as the shaft is moved in the opposite direction, the arms may be withdrawn to a position inside of the post.

30 3. In a device of the class described, the combination of a body portion, a shaft rotatably mounted in the body portion and capable of vertical movement therein, arms pivotally mounted near the lower end of said shaft and connected therewith, so arranged 35 that as the shaft is rotated in one direction the arms may be forced from a position in-

side of the post to a position partially outside of the post, and as the shaft is rotated in the opposite direction, the arms may be withdrawn to a position inside of the post, and 40 means for rotating said shaft.

4. In a device of the class described, the combination of a body portion having a V-shaped lower end, two openings extending through the lower part of said body portion 45 and adjacent to said V-shaped portion, a supporting-arm, an anchor-support extending across the interior of said body portion, having a screw-threaded opening therein, a screw-threaded shaft mounted in said anchor-support 50 and designed to coact with the screw-threaded portion thereof, anchor-arms pivotally mounted near the lower end of said shaft and connected therewith designed to work in the openings in the lower end of said 55 body portion as the shaft is rotated.

5. In a device of the class described, the combination of a body portion having a V-shaped lower end and two openings extending from the exterior to the interior of said 60 body portion, anchor-arms designed to work in said openings mounted on the interior of said body portion, a screw-threaded shaft, means for supporting said screw-threaded shaft on the interior of said body portion, and 65 means for rotatably and pivotally connecting the lower end of said shaft with said arms, for the purposes stated.

RICHARD WILTSE.
